P. SCHNEIDER

COMBINED STEPLADDER AND IRONING BOARD

Filed Oct. 9, 1922

Patented Aug. 14, 1923.

1,464,629

UNITED STATES PATENT OFFICE.

PETER SCHNEIDER, OF LAWRENCEBURG, INDIANA.

COMBINED STEPLADDER AND IRONING BOARD.

Application filed October 9, 1922. Serial No. 593,313.

To all whom it may concern:

Be it known that I, PETER SCHNEIDER, a citizen of the United States, residing at Lawrenceburg, in the county of Dearborn 5 and State of Indiana, have invented certain new and useful Improvements in Combined Stepladders and Ironing Boards, of which the following is a specification, reference being had to the accompanying 10 drawings.

This invention relates to a combined step ladder and ironing board, and more particularly to a combined step ladder and ironing board support.

15 It is an object of the invention to provide a device of this character capable of being used either as a step ladder or adjusted for use as means for supporting and holding an ironing board.

20 It is another object of the invention to provide a device of this character including a ladder having a supporting member, and wherein movement of the supporting member relative to the ladder is limited by a 25 holding member which also serves as supporting means for an ironing board.

It is a further object of the invention to 30 provide a device of this character wherein the means used to limit movement of the supporting member relative to the ladder also coacts with the ladder independently of the supporting member to provide a support for an ironing board.

35 It is still a further object of the invention to provide a device of this character including an ironing board having means at one end thereof for attachment to a portion of the ladder.

With these and other objects in view, the 40 invention consists in the improved construction and arrangement of parts to be herein-after more particularly described, fully claimed and illustrated in the accompanying drawings, in which:

45 Figure 1 is a side elevation of a combined ladder and ironing board support constructed in accordance with an embodiment of the invention and showing the device used as a support for an ironing board, a portion of the ladder and the ironing board being shown in section;

Figure 2 is a longitudinal sectional view of the device in position for use as a ladder and showing the device partially opened;

50 Figure 3 is a fragmentary bottom plan view of the broad end of the ironing board

showing the fastening means for the ironing board; and

Figure 4 is a section taken on the line 4—4 of Figure 2.

Referring to the drawings, 5 designates a step ladder section of conventional form having a top platform 6 and side members 7 and 8. The central portion of the front edge of the platform 6 is provided with a slot 9, the outer edge portion of the slot and the adjacent front edge of the platform being rounded for a purpose to be hereinafter described.

Secured to the upper ends of each of the 70 side members 7 and 8 of the ladder are brackets 10, each bracket consisting of a strip of material bent substantially U-shaped and having its end portions secured to the upper end portions of the side members 7 and 8 beneath the platform 6. Each arm of the bracket is provided with a flange 11 adapted to be secured to the lower face of the platform 6.

By this means a socket is substantially 80 formed rearwardly of the side members for the reception of the uprights 12 and 13 of a ladder supporting member. The upper ends of the uprights 12 and 13 are pivoted within the sockets formed by the brackets. Pivoted 85 between the upper end portions of the uprights 12 and 13 is a combined shelf and brace member 14 comprising arms 15 which are connected at one end by means of a platform or shelf 16. The opposite end portion of 90 each arm has its outer face and a portion of its upper face cut away, to provide an extension 17 and a shoulder 18. The shoulder 18 of each arm is adapted to engage the rear edge of the top step of the ladder and adjacent portions of the side member of the ladder to prevent movement of the supporting member toward the ladder. This combined shelf and brace member is intended to

95 swing into parallel relation with the supporting member when the supporting member is folded upon the ladder.

In connection with the supporting member a holding member 19 is used, said member comprising standards 20 and 21 which are connected at their lower ends by a transversely extending brace 22 and obliquely extending braces 23, the obliquely extending braces terminating at the central portion of each standard. The standards 20 and 21 are 105 pivoted at their central portions to the outer faces of the uprights 12 and 13. The stand-

ards are intended to receive the uprights 12 and 13 of the supporting member therebetween. Pivoted to the outer face of the side members 7 and 8 of the ladder and the inner faces of the lower end portions of the standards 20 and 21 are break joint braces 24. It will be noted that the pivoted ends of the braces 24 of the standards 21 and 22 are disposed a considerable distance below the pivotal connection of the standards to the uprights of the supporting members, so that there is no danger of the device accidentally folding.

When the device is used as a ladder, the supporting member is swung outwardly at an angle to the ladder and into engagement with the braces 22 and 23 of the holding member, whereupon the break joint braces are swung into position so as to hold the supporting member through the medium of the holding member against movement relative to the ladder. The shelf and brace member is then swung into engagement with the top step of the ladder, thus locking the ladder in its extended position. It is also desired that the holding member cooperate with the ladder to provide supporting means for an ironing board 25. In this connection the ironing board is provided with a cleat 26 adapted to serve as a clamping member. This cleat is disposed adjacent the broad end of the ironing board and on the lower surface of the ironing board. The lower surface of the broad end portion of the ironing board is provided with an elongated recess 27 in which a latch member 28 is disposed. This latch member consists of a length of material having one end portion thereof extended at right angles to provide a lip 29, while the opposite end portion is revertedly curved to provide a jaw 30. The latch member is also provided with a longitudinally extending slot 30^a. A cam member 31 is pivoted to the ironing board 25, the pivot pin 32 of said member extending through the slot 30^a of the latch member 28. The slot 30^a is positioned so that the cam surface of the cam member will engage the lip 29 to urge the jaw member 30 toward the cleat 26.

To attach the ironing board to the device the ladder supporting member is swung toward and into engagement with the ladder and the holding member swung outwardly substantially at right angles to the supporting member. In this instance the break joint braces 24 assist in limiting the movement of the holding member relative to the ladder. This disposes the ladder and its supporting member, together with the shelf 6, in an inclined position and also causes the free ends of the standards 21 and 22 to project above the side members of the ladder. The ironing board 25 is then applied to the ladder, the jaw member 30 extending

through the slot 9 and embracing the rounded edge portion of the platform 6. The board is then moved into engagement with the ends of the holding member, whereupon the cam member may be operated to urge the cleat 26 into binding engagement with the edge of the platform, thus firmly holding the ironing board on its support and in the desired horizontal position.

From the foregoing it will be readily seen that this invention provides a novel combined step ladder and ironing board support, wherein the means used to support the ironing board are also used to support the ladder in its extended position. These parts are so arranged that they may be readily folded into a compact form so as to occupy no more space than the conventional step ladder structure when the ladder is not in use. In addition to this the securing means of the ironing board is of such a nature that it is impossible for the ironing board to become accidentally disengaged from its support. All of these features are possessed by a device which is simple and compact.

What is claimed is:—

1. A combined ladder and means for supporting an ironing board comprising a ladder, a supporting member pivotally connected to one end portion of the ladder, and a holding member pivoted at its central portion to the upper portion of the supporting member, break joint braces connecting the holding member to the ladder, and braces carried by the holding member and adapted to engage the supporting member to limit movement of the supporting member relative to the ladder.

2. A combined ladder and means for supporting an ironing board comprising a ladder, a supporting member comprising a pair of spaced uprights pivoted at their upper ends to one end portion of the ladder, the opposite ends of said uprights being adapted to engage the ground, a holding member comprising a pair of spaced standards pivoted to the outer faces of the supporting member the lower ends of said standards terminating above the lower ends of the supporting uprights, brace means connecting the standards of the holding member to each other, said brace means being adapted to engage the uprights of the supporting member to limit movement of the supporting member away from the ladder, break joint braces pivoted at one of their ends to the ladder and at their opposite ends to the standards of the holding member for limiting movement of the holding member relative to the ladder.

3. A combined ladder and means for supporting an ironing board comprising a ladder including a top platform, a slot disposed centrally of the forward edge of the top platform, a supporting member comprising

a pair of spaced uprights pivoted to one end portion of the ladder, a holding member comprising a pair of spaced standards pivoted to the outer faces of the supporting member, brace means connecting the standards of the holding member to each other, said brace means being adapted to engage the uprights of the supporting member to limit movement of the supporting member away from the ladder, break joint braces pivoted at one of their ends to the ladder and at their opposite ends to the standards of the holding member for limiting movement of the holding member relative to the ladder, the upper end portions of the standards of the holding member being arranged to extend above the ladder when the ladder is disposed in an inclined position to provide supporting means for an ironing board, said

ironing board having a cleat disposed on the lower face thereof adjacent one end, a latch member slidable beneath the cleat, said latch member having a jaw on one end and a lip on its opposite end, a cam member pivoted to the ironing board, the pivot of said cam extending through the latch member, said ironing board being arranged to engage the top platform of the ladder and the upper ends of the standards, the jaw of the latch member being adapted to extend into the slot of the top platform, said cam member urging the jaw member and the cleat into binding engagement with the top platform of the ladder.

In testimony whereof I hereunto affix my signature.

PETER SCHNEIDER.
